(57) **CLAIM**

The ornamental design for a belt worn pouch, as shown and described.

DESCRIPTION

FIG. 1 is a perspective view of a belt worn pouch, showing my new design;

FIG. 2 is a front elevation view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom view thereof;

FIG. 8 is a perspective view of a belt worn pouch, shown worn upon a person; and,

FIG. 9 is a front elevational view of an alternate embodiment thereof, shown with a closure flap on top of the closure fastener shown in FIGS. 1-8.

The parts of the drawings shown in dotted phantom lines are shown for environmental purposes only, and form no part of the claimed design.
